BOTTLE CARRIER

Gordon W. Howell, Seattle, Wash.

Application January 24, 1944, Serial No. 519,490

2 Claims. (Cl. 294—87)

1

My invention relates to improvements in a bottle carrier of the type operable to suspend a bottle by its neck, and, more particularly, a bottle carrying device that engages a bottle about its neck below the usual ridge thereon and is locked in gripping position by gravity mechanical means.

While in the prior art there are many bottle carrying devices, it has been my experience that they are too complicated of construction or operation, that they fail to provide a positive gripping action to preclude unlocking when handled roughly, that such earlier devices require materials that are critical in the present war circumstances, that they do not satisfactorily accommodate several bottles or one or two without alteration of the relation of parts, and for further obvious reasons such as high cost of manufacture, limited utility, and the like.

Having in mind the defects of the prior art, it is an important object of this invention to provide a bottle carrier that is easily engaged about a bottle neck and is locked thereon by means actuated by merely lifting the carrier and such bottles or bottle as may have been engaged.

A further object of the invention resides in the provision, in a bottle carrier of the type mentioned, of a pair of relatively movable members that receive and are locked to a bottle without requiring manual force in so doing.

Still another object of the invention is to provide, in a bottle carrier as described, a unique bottle receiving and engaging slot that will support a bottle by its neck ridge but which can be removed from a bottle thus suspended rapidly and easily without requiring great dexterity.

The foregoing objects and others ancillary thereto I prefer to accomplish as follows:

According to a preferred embodiment of my invention, I provide in a plate a bayonet slot whose largest dimension is sufficient to accommodate the largest dimension of a bottle neck collar or ridge to be engaged and whose smallest dimension is substantially that of the bottle neck less the collar whereby, in introducing and removing a bottle from the slot, the largest dimensions is employed and, for carriage, the neck of the bottle to be carried in suspension is disposed in the smallest part of the slot with the collar above the slot. A plurality of these slots may be incorporated in a single plate so that many bottles may be carried by means of but a single carrier plate. For urging the bottle neck into the smallest dimension of the slot a pusher member is employed and is, preferably, a member that operates to press upon or draw the bottle neck when the device is lifted. This portion of the invention assumes more than one form as is more particularly shown in the drawings but which can be briefly described at this point. In one form I place under the first plate a second plate

2

having an opening which will accommodate the largest dimension of the bottle neck collar and which is movable relative the first said plate. The two plates are spread slightly apart when a bottle is being engaged and are drawn into face to face contact and moved sideways relative each other when a bottle is to be locked therein. Preferably, in this form of the invention, the two plates are held together and moved by means of flexible handle member by which the carrier and any engaged bottles may be carried. Another form of the invention employs the same principle of drawing the bottle neck into the smaller portion of a bayonet slot but, in this case, such action is accomplished by a loop extension of the flexible handle member which loop passes around the bottle neck and is drawn tight by the weight of the bottle and the carrier when the same are lifted for carriage.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which

Figure 1 is a view in perspective of one form of my bottle carrier;

Figure 2 is a plan view of a portion of the carrier of Figure 1 in the open position;

Figure 3 is a view similar to Figure 2 showing the carrier in the closed or locked position;

Figure 4 is a perspective view of another form of carrier embodying the principles of my invention;

Figure 5 is a cross sectional view of the carrier of Figure 2 as though taken in the plane indicated by numbers 5—5;

Figure 6 is a view similar to Figure 5 but taken in the plane of Figure 3 indicated 6—6;

Figure 7 is a fragmentary plan view of the carrier of Figure 4;

Figure 8 is a sectional view as though taken on line 8—8 of Figure 7, with the device in the closed position, and

Figure 9 is a view similar to Figure 8 but showing the device in the open position.

Referring to Figures 1, 2, 3, 5 and 6 of the drawings, wherein I show a preferred form of my invention, it will be seen that the carrier comprises a pair of superposed plates having bottle receiving openings and handle means for grasping the carrier as well as for actuating the parts of the same. The numeral 10 designates the carrier plate which here has a plurality of bayonet slots or openings 11 having the enlarged portion 12 and the reduced or locking portion 14. Portion 12 is of a size to accommodate a

bottle neck and the usual ridge around or adjacent the mouth. Portion 14 is of a size, reduced by comparison to portion 12, that approximates the external dimension of the bottle neck below its usual collar or ridge. Below plate 10 is the locking plate 16 which has a plurality of openings 18 all substantially the same size as portion 12 of the bayonet slot openings just described.

Plates 10 and 16 are movable apart and together as well as longitudinally relative each other. It is to be noted that the bayonet slots 11 in plate 10 extends lengthwise of the plate so that, when a bottle is engaged in any opening, portion 12 receives the bottle to be gripped for suspension and either the plate moves so that the reduced opening portion 14 is slipped under the bottle neck ridge, or the bottle is moved into the reduced portion 14. In either event the bottle is retained for carriage in the reduced opening portion 14, by being pressed from the opposite side, by the wall of opening 18 as illustrated in Figure 6 which is to be compared with Figure 5 wherein is shown the relation of the plates to the bottles at such times as the bottles are being received or discharged. It will be apparent in changing from the relation shown in Figure 5 to that of Figure 6 that the plates are brought not only into face to face contact but also have been moved lengthwise of each other so that the openings 12 and 18 which were previously aligned are in Figure 6 disaligned and 18 registers under the reduced opening portion 14.

Such movement is accomplished by the flexible handle loop 20 which has its ends passed through openings 22 in plate 10 and openings 24 in plate 16, said loop ends being knotted or otherwise anchored to the underside of the latter. When the plates 10 and 16 are as shown in Figure 5 the handle loop 20, usually formed of cordage, is distorted to the side between the superposed plates which are spread apart. To move the plates to the relation of Figure 6, the operator need only lift on the handle loop 20 whereupon plate 14 is lifted toward plate 10 and, in the usual course, the latter is caused to shift to the side in a manner that holes 22 and 24 register and bayonet slot portion 14 engages under the neck ridge of each bottle.

I have stated earlier that the action is one produced by gravity. I do so because it is my observation that when bottles are to be locked into the carrier the operator need only lift on the handle loop 20 which raises plate 10 and simultaneously shifts it lengthwise of the bayonet slots to cause the reduced slot portion 14 to partially encircle the bottle neck under the ridge. Next the cordage between the plates is drawn through the holes 22 and plate 16 is simultaneously raised toward the underside of plate 10 during which movement it also shifts longitudinally of the bayonet slot openings but oppositely to the shift of plate 10. It will be seen that this action precludes movement of the neck of the bottle relative the reduced portion of the slot so long as the plates are in face to face contact.

When a plurality of bottles are engaged as shown in Figure 6 they and the carrier may be lifted and carried or set down and again lifted without any of the bottle becoming disengaged. However, when it is desired to disengage the bottles, that may be accomplished with facility merely by manually shifting plates 10 and 14 in

the manner suggested in Figure 5 and the carrier may be lifted off the bottles or even a single bottle may be removed from the carrier.

Turning now to Figures 4, 7, 8 and 9, wherein is shown an alternative form of my invention, the numeral 30 designates a carrier plate having a plurality of bayonet slot openings 32 which each comprise an enlarged portion 34 and a reduced portion 36. Bottles are engaged in these openings as before described but, in this instance, the means for accomplishing and holding this engagement is different. For this purpose I employ handle loop 38 which passes through openings 40 on that side of slots 32 which has the smaller opening 36. The lower portions form loop 42 which, when bottles are engaged and held as in Figures 8 and 9, draws the bottles from the enlarged opening portion 34 into the reduced portion 36 when a pull is applied to handle loop 38. To release a bottle thus gripped the operator need merely grasp the loop 42 and draw a portion of loop 38 downward through the openings 40 and the bottles may be removed.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Having thus described my invention, I claim:

1. A bottle carrier, comprising: a body portion for supporting bottles by their necks or rims; the body portion including apertured upper and lower members of flat sheet material slidably adjustable longitudinally one relative to the other into bottle receiving and bottle carrying positions; a flexible handle passing through said upper member and being secured to said lower member, said handle operating to move said member longitudinally into locking position when said device is lifted by said handle.

2. A bottle holder and carrier, comprising: two juxtaposed sheets face to face and relatively shiftable in their planes, said sheets having overlapping openings providing passages through the sheets which may be expanded or contracted by the shifting of the sheets, said passages when expanded enabling the heads and necks of bottles to be passed therethrough and when contracted enabling the sheets to engage the neck and prevent withdrawal of the bottles, and a handle for the carrier consisting of a cord passing freely through apertures in the top sheet and secured to the under sheet, the apertures being so located that a pull on the handle cords so shifts the sheets to bottle-gripping and carrying position and maintains them in that position while the bottles are being carried.
